UNITED STATES PATENT OFFICE.

GAVIN SPIERS MACMILLAN, OF NEW YORK, N. Y.

PAD.

1,077,537.

Specification of Letters Patent.

Patented Nov. 4, 1913.

Application filed January 3, 1912. Serial No. 669,237.

To all whom it may concern:

Be it known that I, GAVIN SPIERS MACMILLAN, a citizen of the United States, residing in the borough of Manhattan, in the city, county, and State of New York, have invented certain new and useful Improvements in Pads, of which the following is a full, clear, and exact description, reference being had to the accompanying drawings, 10 forming a part of this specification.

My invention relates to improvements in pads, and more particularly refers to a special form of pad most suitable for holding gummed labels for druggists and others; 15 and has for its primary object to provide an improved form of pad for assembling gummed labels, such as to insure their lying permanently flat and convenient to use and to handle.

20 A further object is to provide, in pads formed with gummed labels carrying stubs at opposite ends and separated from the same by perforated or otherwise weakened lines, means for facilitating the detaching 25 of the labels from the stubs simultaneously at both ends, and for preventing the tearing of the same.

It is well known to druggists, and to other 30 large users of gummed labels, that the keeping of considerable quantities of gummed labels of different kinds, is a source of great trouble and inconvenience. The labels have a tendency to curl, and when kept in bunches held together by means of a rubber 35 band, as commonly done, it is extremely difficult to quickly remove a single label from a bunch. It is also quite difficult, by the use of loose labels, to prevent the mixing 40 of the different kinds, unless the same are very carefully stored away in separate drawers or compartments, and this necessarily entails the loss of much valuable 45 space.

The double stub mounting which I provide, as I have pointed out, serves also most conveniently for carrying cards, advertising labels, etc., inasmuch as I have found that by providing notches at the ends of each line of perforations, each card or label is readily 50 detached, no amount of care whatsoever being required in the operation; it is sufficient just to quickly pull it out, quite in the same manner as if the labels were not at all attached, to obtain a clear blank, without danger of tearing the same.

Cards mounted in my improved manner

are always protected, and offer therefore a clean surface, contrarily to what usually happens when the same are carried loose in the pocket, and often handled.

Referring to the drawings, Figure 1 is a view in perspective of a label pad in which the holding device is glued to the stubs; Fig. 2 is a view in perspective of another pad made in accordance with my invention, 55 in which the holding device, which may also be formed with a cover as shown, is secured to the stubs by means of clasps or other separate clamping devices; Fig. 3 is a detail front view in elevation, partly broken away, 60 of a portion of a pad made in accordance with my invention, in which the backing member and the holding device are constituted by two separate parts; and Fig. 4 is a perspective view illustrating a multiple pad 65 formed by several individual sections made according to my invention.

In Fig. 1, my improved block or pad is formed of a series of sheets or labels 10, provided at each end with stubs 11, which are separated from the same by means of perforated or otherwise weakened lines 12, 13. At each end is a holding device engaging the stubs firmly, which is shown integral with the back of the pad 14. This is 70 bent at the two ends so as to form two retaining strips 15, 16, overlapping the stubs, and secured to the same by means of glue, or in any other suitable manner.

In assembling the pad, I prefer to separate the labels by means of sheets of paper 75 rendered non-adhesive by previously treating the same with oil, paraffin, or like substances, to prevent the labels from adhering to each other. As there is usually no particular pressure on the labels, it is not essential in all cases to provide these separating sheets. The labels may be, and usually are, assembled with their entry or ungummed surfaces uppermost.

At the ends of perforated lines 12, 13, I provide notches 17, 18, 19, 20, which greatly facilitate the detaching of labels 10 from their stubs. By taking hold of the labels on one of the sides, as at 21, and by pulling 80 away the same, each label will be readily detached without the slightest tearing, or other unsightly injury to the paper or fabric of which the label may be composed. Therefore my device, besides providing a 85 most convenient means for holding labels or cards so as to prevent their curling or creas-

ing, and for keeping the same in a handy form, also provides simple and efficient means for readily detaching the same.

I am aware that notches at the end of 5 perforated lines have been heretofore used in devices of this character; but the same have not been embodied in pads in which the sheets or labels are held at two ends where the sheets or labels are intended to be at the 10 same time detached from both ends. In this particular form of pad I have found this detail to be essential in order to prevent tearing, and in order to permit the labels to be readily detached without any unnecessary loss of time. The depth of these notches should be such as to enable, in conjunction with the perforated lines, ready and substantially simultaneous detachment of each 15 label from both its holding stubs, without mutilating the label and without carrying away portions of the stubs. In a specific embodiment of the invention the notches may be deep enough to permit the free edges of the labels in the pad to separate slightly 20 from one another as in the manner illustrated in Fig. 1, whereby the edges of the labels may be easily grasped between the fingers, thus facilitating materially the detachment of the individual labels.

Fig. 2 illustrates a pad in all respects similar to that shown in Fig. 1, mounted in a slightly different manner. Instead of gluing the sides 22, 23, and the retaining strips 24, 25 to the stubs 26, I attach the holding device to the pad by means of clasps 27. When desired, to insure the neat appearance of the exposed label or card, the holding device can be provided with a cover 28, attached to one of the retaining strips 24 by 40 means of a flexible hinge 29, or in any other suitable manner.

Fig. 3 illustrates a preferred form of mounting my improved pad. In this case the same is reinforced by a backing member 30, and the assembling is obtained by means of a retaining sheet of paper or fabric passing over said backing member, bent around the ends of the stubs 31, and glued to the same; said retaining member is designated 45 in the drawing by numeral 32.

It is obvious that when convenient, and when considerable quantities of labels are to be kept together, several pads of the same, or of different kinds of labels can be assembled end to end in the same holding device, of a width proportional to the length of each pad, and sufficiently long to afford a backing and retaining strip for several pads. This type of multiple pad is illus-

tated in Fig. 4 where 34, 35, 36, are individual pad sections each provided with end stubs 37, 38, and mounted in a holding device 39, provided with two retaining strips 40, 41, common to all said pad sections and retaining the same in the manner previously described:

Each form of holding device shown has its particular advantages, from a manufacturing standpoint or otherwise; the form shown in Fig. 1 is cheaper than that shown in Fig. 2, inasmuch as it requires a thinner material for the holding member, and the gluing requires less labor than the punching and the inserting of clasps 27; but the form shown in Fig. 2 has the advantage of an interchangeable cover or holder, which can be used over and over. The mounting shown in Fig. 3 is lighter and stronger than that of Fig. 1, and therefore is the one which I prefer to use in most of the cases. In view 50 of these considerations however, I do not desire to confine myself to any particular form of mounting or holding device in connection with my pad, and reserve to myself the right of using for this purpose all such means as may fairly enter into the scope of the appended claims.

Having thus described and ascertained the nature of my invention, what I claim as new, and desire to secure by Letters Patent 55 of the United States is:

1. A block or pad comprising a plurality of gummed labels each provided with stubs at two opposite ends, a holding device having two retaining strips overlapping said stubs, weakened lines adjacent to the inner edge of said retaining strips separating said stubs from said gummed labels, notches at the ends of said weakened lines, and means for securing said gummed labels and holding device together; substantially as described.

2. A block or pad comprising a plurality of gummed labels disposed with their entry surfaces uppermost and each provided with a stub at each of two opposite edges, weakened lines between each of said labels and both of its stubs, a relatively deep notch being provided at an end of each such weakened line and extending inwardly from the edges of the label, and means engaging opposite ends of said pad for binding said stubs.

GAVIN SPIERS MACMILLAN.
